TIE FORMER

William T. Fallon, Douglaston, Long Island,
N. Y.

Application April 29, 1939, Serial No. 270,751

1 Claim. (Cl. 223—111)

My present invention relates to men's furnishings, and has particular reference to a novel tie former for facilitating the proper knotting of a tie.

5 It is the principal object of my invention to provide a convenient tie former for use in facilitating the knotting of a tie.

It is a further object of my invention to provide a simple arrangement for insuring the 10 formation of a centrally positioned dimple in the tie adjacent the knotted portion thereof.

Another object of my invention is to provide a simple device which may be readily manufactured at low cost, and which can be sold at 15 a reasonable price.

With the above and other objects and advantageous features in view, the invention consists of a novel arrangement of parts more fully disclosed in the detailed description following, in 20 conjunction with the accompanying drawing, and more specifically defined in the claim appended thereto.

In the drawing:

Fig. 1 represents a view showing a knotted tie, 25 with the novel tie former in place;

Fig. 2 is a perspective view of the novel tie former, the parts being in open position; and

Fig. 3 is a side view thereof, the parts being in relatively closed position.

30 It has been found desirable to provide a tie former which may be readily attached to the tie during the knotting operation, and which holds the tie in position so that the completed knot will provide a centrally positioned dimple in the front portion of the tie.

I have devised a simple and inexpensive contrivance which may be readily attached to the tie during the knotting process, and which may be readily removed therefrom after the tie has 40 been knotted.

Referring to the drawing, the tie in its knotted form is indicated at A, and the novel tie former is designated 10. The tie former includes an upper plate portion 11, a lower plate portion 12, 45 and a handle 13, the upper plate portion being corrugated so as to provide a centrally positioned and relatively sharp V-cut 14, and the lower portion being similarly corrugated, and having two relatively sharp curves 15 and a central rounded portion 16 therebetween. Each of the plate portions 11 and 12 is preferably of tapered form, the plate portions being broad at the rear end, and tapering towards the front as disclosed in Fig. 1; the handle 13 is preferably made of 50 resilient spring wire, with its ends respectively soldered or otherwise secured to the upper and

lower plate portions. The wire handle has a central coil 17, whereby the upper and lower parts 18 and 19 of the wire are normally urged to relatively closed position, so as to retain the upper and lower plate portions in closed position. 5

When the upper and lower parts of the handle adjacent the coil end 17 are pressed together by the fingers, the lower part 19 will rise in a retaining loop 20 provided in the lower part 19, and separate the two plate portions to permit mounting on a tie as hereinafter described. When the pressure on the handle is released, the two plate members will return to relatively closed position. 10

In using the novel tie former, the tie is first knotted loosely, and the tie former is then 15 clamped closely adjacent the knot, and over the front tie portion, which is received between the upper plate portion 11 and lower plate portion 12. The tension of the coil 17 presses the plate portions and thus corrugates the upper portion of 20 the tie which is received therebetween; the tie knot is now completed, the knotting process drawing the tie portion forwardly, but without ironing out the dimple resulting from the coacting upper and lower plate portions, whereby the 25 novel tie dimple former may be removed after the tie is completely formed to leave the upper portion of the tie with a perfectly formed, centrally positioned dimple.

While I have disclosed a specific embodiment 30 of my invention, it is obvious that changes in the shape of the dimple forming members, in the shape of the handle part, and in the arrangement for releasably retaining the dimple forming members in proper pressing position and for 35 permitting their separation to facilitate placing of the upper portion of the tie therebetween and withdrawal of the tie former from the knotted tie, may be made without departing from the spirit and the scope of the invention as defined 40 in the appended claim.

I claim:

As a new article of manufacture, a tie former comprising a corrugated top plate tapering towards one end, the corrugations being of an 45 inverted W shape and forming two V's joined at their adjacent edges, to provide a centrally positioned and relatively sharp V cut, a bottom plate having complementary corrugations and being tapered similarly to the top plate and 50 having two sharp curves at the apices of the V's and a central rounded curve at the joined adjacent edges of the V's, and means for resiliently and releasably retaining said plates in superimposed relation.

WILLIAM T. FALLON.
